UNITED STATES PATENT OFFICE.

RAY E. DE CAMP, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL SYSTEM.

1,392,250.

Specification of Letters Patent. Patented Sept. 27, 1921.

Application filed Augst 26, 1918. Serial No. 251,429.

To all whom it may concern:

• Be it known that I, RAY E. DE CAMP, a citizen of the United States, and a resident of Wilkinsburg, in the county of Allegheny and State of Pennsylvania, have invented a new and useful Improvement in Control Systems, of which the following is a specification.

My invention relates to control systems and particularly to systems such as those forming the subject matter of a copending application, Serial No. 236,937, of H. D. James, May 27, 1918, and assigned to the Westinghouse Electric & Manufacturing Co.

Figures 1 and 2 of the said application represent motor-control systems in which the acceleration of the motor is effected through the short-circuiting of a resistor by means of a plurality of contactors, the actuating coils of which are energized by the closing of relay members which, in turn, are controlled by a coil in parallel relation to the resistor. When the resistor is entirely shunted, of course, this coil is deenergized, but provision is made for maintaining the relay members closed by means of a coil, the terminals of which are connected across the armature. My invention resides in substituting for this last-named coil a coil that is similarly connected but the circuit of which is completed only upon the closing of the last relay member. This coil thus remains deenergized so long as the last member remains open.

Fig. 1 is a diagrammatic view of a system arranged according to my invention, and Figs. 2, 3 and 4 are, respectively, a side and an end elevation and a plan view of a preferred relay mechanism employed in connection with the system of Fig. 1. This relay mechanism constitutes the subject matter of my copending application, Serial No. 241,259, current-limit relay, filed June 21, 1918.

Referring to Fig. 1, a motor, the armature of which is shown at 1 and the shunt field-magnet winding at 2, is connected between line conductors 3 and 4, the motor circuit being controlled by a line contactor 5, with a regulating resistor 6 normally in series with the armature 1. A "start" push-button switch controls the closing of the contactor 5 through an actuating coil 8. The "start" push-button switch may be shunted by means of a switch 9 mechanically inter-

locked with the contactor 5. One or more contactors 10, 11 and 12 (three are illustrated) control the shunting of successive portions 13, 14 and 15 of the regulating resistor 6 through the medium of actuating coils 19, 20 and 21. A coil 22 is connected in parallel circuit with the resistor 6, and a second coil 23 is connected, in circuit with an external resistor 24 of high resistance, across the line conductors 3 and 4. The energizing of the coil 22, as explained below, causes the successive closing of relay members 25, 26 and 27, in accordance with the strength of the current passing through the coil 22. The relay member 27 controls the closing of the circuit of the coil 23. The coil 19 and the relay member 25 are series-connected in a circuit extending from the line conductor 3, through the coil 19, the relay 25 and the "start" and "stop" push-button switches, to the line conductor 4. The coil 20 and the relay member 26, as well as the coil 21 and the relay member 27, are in parallel relation to the coil 19 and the relay member 25. The pressing of the "stop" push-button will stop the motor.

The preferred form of device for use in the system of Fig. 1 is illustrated in Figs. 2, 3 and 4. Briefly, it comprises a coil, the current flowing through which creates a magnetic field which causes an armature to close, thereby releasing a plurality of armatures, each bearing a relay contact member. These latter armatures are spring operated to closed-circuit positions, but, owing to the magnetic field above mentioned, the power of the springs is temporarily overcome until the magnetic flux, produced by the electric current, falls to predetermined values. The armatures are thus operated in succession, depending for their operation on the period of acceleration of the motor.

An insulating panel 29 carries two brackets 30 and 31 supporting the coils 22 and 23 which, when energized by current flowing through them, create magnetic fields for attracting an armature 32 and any desired number of additional armatures 33, 34 and 35. A compression spring 36 is adjustably mounted upon a non-magnetizable rod 37, slidably mounted in projections 38 and 39, which are rigidly connected to, or are integral parts of, the bracket 31. The projection 38 serves also as a pole piece for the armature 32, and the projection 39 as a pole 110

piece for the armatures 33, 34 and 35. A bar 40 is rigidly connected to the rod 37 and normally engages the armatures 33, 34 and 35. The spring 36 thus normally maintains the 5 armatures 33, 34 and 35 in open position, with the members 41, which are carried by these armatures, in contact with the pole piece 39. The members 41 are preferably of non-magnetizable material to prevent 10 "freezing."

The armature 32 is provided with brackets 42, which are pivotally mounted upon the bracket 30, and is normally retained in the broken-line position, (Fig. 2), by a 15 weak spring 43. The bracket 30 supports a non-magnetizable, U-shaped member 44, between the arms of which are pivotally mounted the armatures 33, 34 and 35, which carry, respectively, the movable contact 20 members 45, 46 and 47 of the relay members 25, 26 and 27, shown in Figs. 2, 3 and 4 as closed. The stationary contact members 48, 49 and 50 of the relay members 25, 26 and 27 are mounted upon the insulating 25 panel 29. Springs 51 are attached to longitudinally adjustable members 52 and to the other ends of the members 41. The pole piece 39 is provided with longitudinally adjustable members 53 to regulate air gaps 54 30 between these members and the corresponding armatures. By means of this adjustment, or by means of the members 52, the action of the magnetic flux produced by the coils 22 and 23 may be so regulated that 35 the armatures 33, 34 and 35 will be operated in proper sequence.

The operation is as follows: Upon the actuation of the "start" push-button, the coil 8 is energized by means of a circuit extending 40 from the line conductor 3, through the coil 8 and the "start" and "stop" push-buttons, to the line conductor 4. The contactor 5 and the switch 9 are thereupon closed, the latter creating a short-circuit for 45 the "start" push-button, which may thereupon be released, and the former closing the motor circuit. Current then flows from the line conductor 3 through the armature 1, the resistor 6 and the contactor 5, to the line conductor 4. A circuit is also established 50 through the coil 22, in parallel to the resistor 6. The energizing of the coil 22 creates a magnetic field which attracts the armature 32 to the pole piece 38 (Fig. 2). 55 The rod 37 (Fig. 2) is thereupon pressed inwardly in opposition to the force of the spring 36, forcing the bar 40 away from the armatures 33, 34 and 35. The motion of the armature 32 is from the broken-line to 60 the full-line position of Fig. 2. If the current is above a previously selected safe value, the flux of the magnetic field will overcome the forces of the springs 51, and the armatures will remain with the stops 41 in engagement with the pole piece 39. As the

motor accelerates and the current begins to die down, the magnetic flux set up by the coil 22 becomes weakened. After a time, when the flux has decreased to a predetermined value, the spring 51, attached to one 70 of the armatures, say the armature 33, will overcome the flux of this field, so that the relay member 25 will be closed. The time when this operation occurs depends upon the air gap 54 and the tension of the spring 75 51. The relay members 26 and 27, however, remain open.

A circuit now exists from the line conductor 3, through the coil 19, the relay member 25, the switch 9, and the "stop" 80 push-button, to the line conductor 4. The closing of this circuit energizes the coil 19 which causes the closing of the contactor 10 and this, in turn, creates a shunt circuit for the portion 13 of the resistor 6. The motor 85 then further accelerates to decrease the voltage across the terminals of the coil 22 and thus weaken the magnetic field in the neighborhood of this coil, which permits the closing of the relay member 26. A circuit is 90 then made from the line conductor 3, through the coil 20, the relay member 26, the switch 9, and the "stop" push-button, to the line conductor 4. The coil 20, thus becoming energized, causes the closing of the 95 contactor 11 and the consequent shunting of the resistor 14. After the motor is further accelerated, the magnetic field surrounding the coil 22 is again weakened and the relay member 27 is closed, creating a 100 circuit from the line conductor 3, through the coil 21, the relay member 27, the switch 9 and the "stop" push-button, to the line conductor 4, thereby causing the energization of the coil 21 and the closing of the 105 contactor 12. The resistor 6 is then entirely shunted from the armature circuit, and the armature 1 is connected directly across the line.

The shunting of the entire resistor 6 de- 110 energizes the coil 22 and tends to release the armature 32 (Fig. 2) and open the relay members 25, 26 and 27. This is prevented in my system by the coil 23 the circuit of which, closed by the relay member 27, ex- 115 tends from the line conductor 3, through the coil 23, the resistor 24, the relay member 27, the switch 9 and the "stop" push-button, to the line conductor 4.

To stop the motor, the "stop" push-button switch is depressed to open the circuit of the coil 23. The spring 36 then actuates the armature members 33, 34 and 35 to their respective open positions. Since the armature members correspond to the relay members 25, 26 and 27 of Fig. 1, the relays open the circuits of the corresponding actuating coils of the accelerating switches, and the latter open to insert the resistor 6 in circuit with the motor. The circuit of the 120 125 130

actuating coil 8 of line switch 5 is opened, also, by the "stop" push-button switch.

I claim as my invention:

- 6 1. In a motor-control system, the combination with an electric circuit including a resistor, of a circuit comprising a switch for short-circuiting said resistor, and means for maintaining said resistor short-circuited, said means comprising a relay member for controlling said switch and a coil energized in accordance with the position of said relay member. 55
- 10 2. In a motor-control system, the combination with an electric circuit including a resistor, of a circuit comprising a circuit-controlling device for effecting the shunting of said resistor, an actuating coil for said device in parallel relation to said resistor, and means controlled by the closing of said device for maintaining the latter closed. 60
- 15 3. In a motor-control system, the combination with an electric circuit including a resistor, of means comprising a relay member for effecting the shunting of said resistor, an actuating coil for said relay member in parallel relation to said resistor, and a coil adapted to be energized upon the closing of said relay member to maintain the latter closed. 65
- 20 4. In a motor-control system, the combination with an electric circuit including a resistor, and means comprising a plurality of relay members for successively effecting the shunting of portions of said resistor, of means dependent upon the voltage across said resistor for keeping said relay members open, means for successively closing said relay members when the said voltage falls below predetermined values, and a coil energized upon the operation of the last of said relay members to close for maintaining said relay members closed when said resistor has been completely shunted. 70
- 25 5. In a control system, the combination with an electric motor, a resistor in circuit therewith, and means comprising a plurality of switches for successively shunting portions of said resistor, of a coil in parallel relation to said resistor, means dependent 75
- 30 40 upon the value of the current in said coil 80
- 35 45 6. In a motor-control system, the combination with a motor armature and a resistor in circuit therewith, of means comprising a plurality of switches for shunting said resistor, a plurality of relay members for controlling said switches, and a holding coil for said relay members, one of said relay members being adapted to close the circuit of said holding coil. 85
- 40 7. In a motor-control system, the combination with a motor having an armature and a resistor in series therewith, of means comprising a plurality of switches for short-circuiting said resistor, an actuating coil for each of said switches, a relay member for closing the circuit of each of said coils, a coil in parallel with said resistor for controlling said relay members, and a coil controlled by the last of said relay members to close for controlling said relay members. 90
- 45 8. In a motor-control system, the combination with an electric motor having an armature, and a resistor in series therewith, of a plurality of switches for controlling said resistor, a plurality of relay members for controlling said switches, and a coil for insuring that said relay members remain closed after being actuated to such positions, said coil being energized upon the closing of one of said relay members. 95
- 50 9. The combination with an electric motor having an armature, a resistor in circuit therewith and a source of current for said motor, of a switch for short-circuiting said resistor, a coil in parallel relation to said resistor for causing the actuation of said switch, and a coil energized by the voltage of said source for maintaining said switch in its actuated position. 95

In testimony whereof I have hereunto subscribed my name this 22nd day of August, 1918.

RAY E. DE CAMP.
